UNITED STATES PATENT OFFICE.

JAMES J. LAWLER, OF SCRANTON, PENNSYLVANIA.

GAS-BURNER-TIP CLEANER.

SPECIFICATION forming part of Letters Patent No. 374,075, dated November 29, 1887.

Application filed February 26, 1887. Serial No. 229,008. (No model.)

To all whom it may concern:

Be it known that I, JAMES J. LAWLER, a citizen of the United States of America, residing at Scranton, in the county of Lackawanna and State of Pennsylvania, have invented certain new and useful Improvements in Gas-Burner-Tip Cleaners, of which the following is a specification, reference being had therein to the accompanying drawings.

10 This invention pertains to certain new and useful improvements in devices for cleaning gas-burner tips; and it consists in the detailed construction, combination, and arrangement of the parts, substantially as hereinafter fully set 15 forth, and particularly pointed out in the claims.

In the accompanying drawings, Figure 1 is a view in side elevation of my invention as attached to a gas-burner. Fig. 2 is a plan view 20 thereof, and Figs. 3 and 4 are details.

In carrying out my invention I employ a ring or collar, A, which has a small set-screw, a, working in an aperture formed therein, whereby the ring or collar can be secured at 25 any desired point or height on the gas-burner to which applied, the adjustability thereof being necessary in view of the variance in sizes of gas-burners.

B is an approximately U-shaped frame or carrier, the forward ends of which have right-30 angularly-disposed arms b, which are provided with slots or apertures in their outer ends for insertion on two oppositely-disposed lugs or protuberances, b', formed integral with the ring 35 or collar A, as shown in Fig. 2.

A knife or cleaner, C, is secured at its rear end between a bent projecting part, d, in the curved portion of the U-shaped frame or carrier, and through an aperture formed in this 40 end of said knife or cleaner and corresponding apertures in the bent projection d is passed the upper hooked end of a strong wire handle, D, the purpose of which will soon appear. The widened cam-like end d' of this knife or cleaner 45 is corrugated transversely, as shown in Fig. 4.

From what has been said it will be seen that by securing the ring or collar A on a gas-burner, as shown, so as to permit the knife or cleaner to pass in and through the slit formed 50 in the tip of said burner, by slightly push-

ing on the wire handle D the pivoted U-shaped frame or carrier will be moved forward, causing the corrugated portion of the knife or cleaner to pass through the slit formed in said tip, thus effectively cleaning the same and freeing it from all dust, sediment, &c., which collect in a greater or less degree in all burner-tips.

By means of my invention a clear and steady light is always obtained, all hinderance thereto 60 being readily removed, and this at but slight expense, thus dispensing with the necessity of substituting new tips or burners when the same become clogged, as aforesaid, and, further, obviating the loss experienced by the breaking 65 of the tips in trying to clean the same.

Having thus fully described my invention, what I claim, and desire to secure by Letters Patent, is—

1. In a device for cleaning gas-burner tips, 70 the ring or collar having a set-screw, a frame pivoted to said ring or collar, and a knife carried by said frame, substantially as shown, and for the purpose stated.

2. The U-shaped frame or carrier having 75 pivotally-secured arms, and a knife or cleaner carried by said frame, arranged substantially as shown, and for the purpose described.

3. In a device for cleaning burner-tips, the knife having a transversely-corrugated por- 8c tion, and the pivoted frame carrying said knife, substantially as shown and described.

4. The combination, with the adjustable ring or collar, of the U-shaped frame pivoted to said ring or collar, and the knife or cleaner carried 85 by said frame, substantially as shown and described.

5. The combination, with the ring or collar having the set-screw, and the pivoted frame or carrier having an apertured projecting por- 9c tion, of the corrugated knife or cleaner and the operating - handle, arranged substantially as shown, and for the purpose set forth.

In testimony whereof I affix my signature in presence of two witnesses.

JAMES J. LAWLER.
